UNITED STATES PATENT OFFICE

MORRIS M. EINSON, OF YONKERS, NEW YORK, ASSIGNOR TO EINSON-FREEMAN CO. INC.,
OF LONG ISLAND CITY, NEW YORK, A CORPORATION OF NEW YORK

DISPLAY DEVICE

Application filed November 28, 1930. Serial No. 498,632.

The present invention relates to a class of display devices which are usually placed on store counters or in store windows for the purpose of advertising merchandise and the invention consists of certain useful improvements in devices of said class.

The improved device is designed with certain objects in view; firstly to provide an attractive design which will produce a true representation of a stack of cartons or containers arranged in rows one above the other so as to give the effect of a pyramid composed of a number of individual cartons or containers for merchandise so arranged that each carton or container is represented separately or distinctively from another. Another object is to produce a device which is collapsible into a flat position in which condition the device is packed for delivery or storage and the construction is so simple that the operator may readily set up the collapsed device without having had previous experience. An additional object is to provide a device which may be economically produced and to facilitate the manufacture, the device is composed of a single sheet of paper-board, for example, which is cut out in the form of single blank. This blank is creased to divide the same up into a number of sections which are folded and united together so as to give the desired appearance of the separate individual cartons stacked as aforesaid.

In carrying out the invention the single sheet blank forms the body of the device and in a preferred form said body is a pyramidal V-shaped structure in which form alone the device may be complete and form its own base of support when set up. The carton representations with this device are arranged in two or more rows on top of each other and to improve or change the design an additional representation of a carton composed of a separate sheet can be added to the bottom row.

In order to increase the display surface of the improved device a separate card may be added at the back of the uppermost carton or cartons so as to provide a display card. The structure, either with or without the added parts, is foldable so as to collapse into a flat condition and when the device is set up for

display a flap provided for each individual carton is inserted into the open top of the respective carton so as to close the cartons and when all the cartons are so closed the device is rigidly retained in its set up condition.

An embodiment of the invention will be more fully described hereinafter with reference to the accompanying drawings, wherein—

Figure 1 is a perspective view showing the improved device in the set up position;

Figure 2 is a perspective view showing the retaining and closing flaps in the open position;

Figure 3 is a front elevation of the set up device;

Figure 4 is a top plan view of the set up device;

Figure 5 is a top plan view of the device in the collapsed or flat position;

Figure 6 is a cross section showing the device partly collapsed;

Figure 7 is a plan view of the blank from which the body of the device is composed;

Figure 8 is a plan view of a separate blank of which an added carton is composed; and

Figure 9 is a plan view of a separate sheet employed as a display card.

Referring to said drawings, the body 20 is made up of a number of forms representing cartons or containers 21. These containers are so represented as to stand out separately from one another and each carton has a covering flap 22. Each of these flaps has a tuck-in end 23 which is inserted into the carton and to limit the depth of insertion of the tuck-in 23, lugs 24 are provided on the flaps 22 and said lugs engage the upper edge of the cartons. The body, as represented in the drawings, is made up of three rows of cartons placed one on top of the other so as to produce a pyramidal design substantially V-shaped in cross section and in this form alone the device may be used as a complete and attractive display device providing its own supporting base so that the device will stand firmly in a set up position for display. A variation in the design of the device is obtained by adding an additional carton 25 which fills the corner of the V-shaped body,

as shown in the drawings. To further improve or change the design of the device, and to offer increased display surface, a show card 26 is secured to the back of the topmost carton.

Referring now particularly to Figures 6, 7, 8 and 9 showing the blanks of which the improved display device is made up. In the preferred form, the improved display device 10 has three rows of carton representations superposed one row above another and the blanks are designed for such a construction. One of these blanks is the main blank B forming the body of the device, said blank being 15 divided into a number of parallel sections or portions by scores or creases and said sections are numbered from 1 to 13 inclusive. C is a separate blank, divided by creased line into two sections 14 and 15 and used for forming 20 the additional or filling carton 25. Another blank D is employed when a show card is to be added to the device. All of said blanks are composed of sheet paper-board and are arranged to fold in the center on a creased 25 or folding line A. When the parts are assembled the different blanks are in alignment so that the assembled device will fold centrally on said creased line A.

In assembling or setting up the main blank 30 to form the collapsed body of the device the different sections are united together, as will be hereafter more particularly described with reference to Figures 6, 7 and 8 wherein the back of the blanks are shown. In the set up 35 position the blank is reversed so that the front or prepared surface of the board is exposed.

The first operation in folding the main blank B is to fold the same on the creased 40 lines a' so as to bring the glue lap a , carried by section 1 over so that it may be secured adhesively to the section 8 where indicated by a'' . The next fold is on crease b' to bring the glue lap b over onto section 1 where indicated by b'' . The folding on the lines b' brings section 13 over section 10 and the glue lap of section 10 is secured at the point c'' on section 13. On the opposite side of the blank section 2 is brought over section 5 where 45 glue lap d of section 5 is secured to section 2 at the point d'' and in both cases the sections 5 and 10 are folded respectively on the lines d' and c' . The folding of the main section on the line A and the additional folding of 55 sections 6 and 9 on the score lines e' will bring the glue lap e of section 6 over the point e'' on section 9 where it is adhesively secured. It should be noted the glue spots a'' , b'' , c'' , d'' , e'' , f'' and g'' are on both surfaces of the 60 blank B and to locate the same, the glue spots appearing on the back of the blank are indicated with cross hatched shading. The additional blank C is now secured to sections 2 and 13 by means of the glue laps f being secured at f'' of the sections 2 and 13.

The blank D is added and this blank is affixed to sections 7 and 8 by securing the glue laps g on the spots g'' . The blanks are so folded and united that the prepared surface of the board only is exposed to present the 70 prepared faces of the various carton representations as indicated in the set up position shown in the drawings. In these set up figures the same reference numerals applied to the blank are used; therefore, the various sections can be readily identified in the set up device. It will be noted that sections 1, 7 and 8 are not exposed in the set up position for these latter sections are at the back of the set 75 up device.

In the operation of the device the body and the added pieces if used, are collapsed all together including the individual representations of the cartons and in which condition the device lies flat and may be shipped or stored with facility. When setting up, the device is folded into a triangular shape on the main or central folding line A. This folding operation will at the same time open each individual carton and in which position the cartons are held by the insertion of the tuck-in or retaining flaps 22-23. The device so set up is rigid even when made of comparatively light stock which is preferably used for the reason that the manufacture and folding operations are thereby made easier than when the device is made of comparatively heavy paper board.

Various modifications may be made in carrying out the constructional details of the invention or in the application of the same other than hereinbefore described and it is therefore to be understood any modification coming fairly within the terms of the appended claims shall be covered thereby.

I claim:

1. A display device of the class described comprising a body composed of a single sheet folded to represent a plurality of separate individual cartons or containers and an added sheet secured to said body foldable so as to form a filling representation of a carton or container.

2. A display device comprising a body composed of a single sheet divided into sections arranged to be folded over each other and united to form a structure representing a plurality of separate individual cartons or containers united together and stacked in a pyramidal form and an added sheet or member secured to said body and arranged to fold therewith forming an additional carton or container whereby the supporting base of said structure is increased.

3. A blank for a display device of the class described composed of a single sheet, said sheet being arranged to fold on a defined longitudinal median line so as to divide said sheet into two halves or parts, one half folding on itself and having the free end thereof

secured to the other half and the latter half also folding on itself and having the free end thereof secured to the first mentioned half, and said halves both having separably folding flaps extending therefrom.

5 4. A display device constructed of a blank according to claim 3 wherein said halves or parts are united together so as to form a collapsible structure which is designed to fold 10 into a set up position and to be retained in that position by folding and engagement of said flaps.

15 5. A display device constructed of a blank according to claim 3 wherein said blank is prepared, folded and set up to form a structure representing a plurality of cartons arranged in a pyramidal form.

20 6. A display device constructed of a blank according to claim 3, said device folding on said median line and said halves or parts 25 folding so as to form a structure having a stepped front and an angular back.

25 7. A display device constructed of a blank according to claim 3, said blank being folded on both of said halves or parts and on said 30 median line so as to form said device with a supporting base when erected, said parts being prepared and folded so as to represent individual cartons arranged in rows one above the other to produce a stacked or stepped pyramidal form, and said flaps when folded and engaged providing means for 35 tentively holding the device in the set up position.

35 In testimony whereof I affix my signature.
MORRIS M. EINSON.
